UNITED STATES PATENT OFFICE.

FLOYD L. SCOUTTEN, OF EAST CLEVELAND, OHIO.

THERMOSTATIC ALARM.

1,301,011.

Specification of Letters Patent.

Patented Apr. 15, 1919.

Application filed March 19, 1915. Serial No. 15,424.

To all whom it may concern:

Be it known that I, FLOYD L. SCOUTTEN, a citizen of the United States, residing at East Cleveland, in the county of Cuyahoga and State of Ohio, have invented a certain new and useful Improvement in Thermostatic Alarms, of which the following is a full, clear, and exact description, reference being had to the accompanying drawings.

10 This invention relates generally to thermostatic alarms, and more particularly to one adapted for application to the outlet flue of a furnace, for the purpose of giving an alarm in case this flue should become overheated. It will be understood however, that the invention is also capable of other applications and uses.

The object of my invention is to provide a simple and efficient alarm device which can 20 be readily applied to the exterior of a flue or pipe and which will, in case of excessive heat, close an electric circuit and sound an alarm bell; and another object of the invention is to provide a device which can be arranged 25 and which will be thoroughly operative in either a horizontal, vertical, or inclined position, thereby providing a device which can be attached to a flue extending in any direction.

30 With these various objects in view, my invention consists in the novel features of construction and the manner of arranging them, all of which will be fully described hereinafter and pointed out in the claims; and 35 while I show and describe one form of device for carrying out my inventive idea it will be understood that certain variations or modifications can be made within the scope of the claims.

40 In the drawings forming a part of this specification

Figure 1 is a perspective view showing the practical application of my invention, the cover being broken away, and Fig. 2 is a sectional view through the device and its cover taken at the expansion post.

In carrying out my invention I employ a base 1 of suitable material, such as asbestos board, said base being of such size and shape 50 as to carry all of the various parts of the alarm. Upon the under side of the base 1, near one end thereof, is a plate 2 of heat conducting metal, such as copper, and connected to this plate and extending through the base 55 is the post 3, also of heat conducting material, said post being tapered at its end and

providing a rest for the lever 4 which is pivoted to a bracket 5, attached to the base adjacent the post 3, said lever carrying a contact 6 at its free end to which is attached the 60 usual construction of binding post 6^a for the connection 6^b leading to an alarm bell (not shown).

Near the opposite end of the base 1 is another bracket 7, to which is attached an arm 65 8 carrying a contact 9 in the form of a spring and provided also with a binding post 9^a from which leads the conductor wire 9^b. Working through the arm 8 and bearing on the contact 9, is an adjusting screw 10 by 70 means of which the position of the contact 9 with reference to the contact 6 can be adjusted.

The alarm device constructed as above described is adapted to be arranged upon the 75 exterior of an outlet pipe or flue of a furnace, said pipe or flue being indicated at 11, and in order to quickly and securely fasten the alarm to said flue or pipe I employ a pair of clamping bands 12, which encircles the 80 flue or pipe and are preferably carried by the protecting cover 15; but it will be distinctly understood that the clamping bands can be arranged in any suitable manner, and, furthermore, that other forms of fastening 85 means may be employed without departing from the spirit of my invention.

In operation the parts are arranged as shown, with the contact 6 beneath the contact 9 but spaced therefrom, the distance 90 between the contacts being determined by the adjusting screw 10, by means of which the device can be adjusted to become operative at any desired temperature within certain limits, it being obvious that, as the temperature rises the post 3 will expand, and, operating upon the lever 4, will cause the contact 6 to engage the contact 9, close the circuit through 6^b and 9^b and ring the bell; also that, if the contacts are brought into 100 very close relation, a slight increase above the normal temperature of the flue will cause the alarm to sound whereas, by separating the contacts more or less a corresponding increase in temperature will be required to 105 close the circuit and sound the alarm.

In order to adapt my alarm device for use upon vertical, as well as horizontal, pipes, I attach a weight 13 to the lever 4 by means of a rod or wire 14 which is bent so 110 as to position the weight adjacent the base, as most clearly shown, the tendency thereof

being to maintain the lever in contact with the expansion post 3 whether the device be used in a horizontal or vertical position or in any position intermediate therebetween.

- 5 When the alarm device is arranged horizontally or upon an incline, this weight may not be necessary, but when the device is arranged vertically it then becomes desirable if not necessary, and as this weight is not 10 excessive I prefer to employ it in connection with the device in all positions of the device.

In order to protect the operative parts from dust, dirt and the like I provide an 15 enveloping cover 15 of any suitable material (such as fiber) connected to the base in any suitable manner, this cover being broken away in Fig. 1 to show the parts therewithin.

20 It will thus be seen that I provide an exceedingly simple, inexpensive, and efficient thermostatic alarm which will accomplish all of the objects hereinbefore referred to.

Having thus described my invention, what 25 I claim is:—

1. An alarm device comprising a substantially non-conducting base, a conducting plate arranged upon the bottom thereof, an expansion member connected to the plate 30 and projecting through the base, a lever resting upon said expansion member and carrying a contact near its free end, an adjustable contact arranged adjacent, but spaced from, the contact carried by the lever, said contacts constituting parts of an alarm circuit 35 and means for connecting the device to a flue or pipe.

2. An alarm device comprising a substantially non-conducting base, a conducting plate arranged beneath the same, an expansion member connected to the plate and projecting through the base, a lever pivotally connected with the base, resting upon the 40

expansion member and carrying a contact, a second contact spaced from the first contact, 45 said contacts constituting parts of an alarm circuit, and means for connecting the device to a flue or pipe.

3. In an alarm device, the combination of a bracket, an expansion device adjacent to said bracket, a lever pivoted to said bracket and adapted to be engaged and supported by said expansion device at a point intermediate of its ends, said lever having a contact adjacent to its free end, a contact 50 coöperating with the first mentioned contact, an arm projecting from said lever, beneath said lever, and a weight on said arm adapted to maintain the latter in engagement with the expansion device in varying 55 angular positions of said alarm device.

4. In an alarm device, the combination of a base, a bracket projecting upwardly from said base, an expansion post projecting upwardly from said base, a lever pivoted to 60 said bracket and extending over said post and having a contact adjacent its free end, a contact coöperating with the first mentioned contact, an arm connected to said lever and extending between the same and 65 the base, and a weight on said arm.

5. In an alarm device, the combination of a bracket, an expansion member adjacent to said bracket, a lever pivoted to said bracket and extending over said member and having 70 a contact adjacent its free end, a contact coöperating with the first mentioned contact, an arm connected to said lever and extending beneath the same, and a weight on said arm.

In testimony whereof, I hereunto affix my 75 signature in the presence of two witnesses.

FLOYD L. SCOUTTEN.
